LOUIS H. MORIN, OF NEW YORK, N. Y., ASSIGNOR, BY MESNE ASSIGNMENTS, TO DOEHLER VENDING MACHINES, INC., A CORPORATION OF NEW YORK

LIQUID VENDER

Application filed March 11, 1929. Serial No. 345,944.

This invention relates more particularly to the dispensing features or the delivery mechanism of a vending machine. A vending machine according to this invention is particularly adapted for vending a liquid in a substantially accurately measured predetermined quantity which will be substantially uniform at each operation of the machine. While the machine shown in the drawings is designed for vending an inflammable liquid, such as gasoline or benzine to fill pocket lighters, it is also similarly adapted for vending other liquids, such for example as perfume. The machine is of a suitable size and proportions 10 to rest upon a counter or the like in a store, and for obtaining a clearer idea of the general nature of the invention, it may as well here be noted that the particular machine shown in the drawings as an embodiment of the invention has an over all height of about one foot and four inches, while the full width of the base is about seven inches.

In carrying out the invention, a visual indicator of the counter type is provided for 25 indicating the number of operations of the machine, such indicator being particularly designed to give such indication up to a very high number.

Among the objects of the invention are effectiveness of operation, simplicity of construction, convenience and inexpensiveness of manufacture, reliability and durability. Other objects and advantages of the invention will hereinafter appear.

The invention includes various features of construction and combinations of parts, as will appear from the following description.

The particular embodiment of the invention illustrated in the accompanying drawings will now be described and thereafter the invention will be pointed out in claims, reference now being had to the drawings, in which:

Fig. 1 is a front elevation of a complete vending machine in which the invention is embodied;

Fig. 2 is a similar somewhat enlarged view partly in section, the upper portion of this section being taken substantially on the zig-zag line 2-2 of Fig. 4;

Fig. 3 is a substantially central vertical section on the line 3-3 of Fig. 2;

Fig. 4 is a plan view of the upper portion of the machine as viewed from above in Fig. 3, without the cover cap and with the cylindrical glass container shown in horizontal section, for clarity of illustration;

Fig. 5 is a vertical section in detail of the pump cylinder and its immediate adjuncts, taken substantially on the inclined line 5-5 of Fig. 4;

Fig. 6 is a somewhat further enlarged detail vertical section of the cylinder without its piston, taken substantially on the line 6-6 of Fig. 5;

Fig. 7 is an incomplete further enlarged view substantially similar in general to Fig. 2;

Fig. 8 bears a similar relation to Fig. 3;

Fig. 9 is a further enlarged detail plan view of the coin carrier together with some of its associated parts, the adjacent portion of the casing wall appearing in horizontal section while the axial end portions of the coin carrier are broken away;

Fig. 10 is a view substantially similar to Fig. 8 with parts omitted and taken in part on a slightly different plane;

Fig. 11 is an enlarged partial vertical section on the line 11-11 of Fig. 8, and

Fig. 12 is an enlarged front elevation of a portion of the indicator front showing the calibrations thereon more completely than could be shown in Fig. 1.

In the liquid vender shown in the drawings as an embodiment of the invention all of the general frame parts, all of the larger operating parts together with several of the smaller ones, may be die-castings of a suitable metal, such as zinc, and all of the remaining parts of the machine are so designed as to be readily manufactured from easily obtainable suitable materials. The particular construction illustrated in the drawings as an embodiment of the invention will now be described in detail with reference to the drawings.

A single hollow die-casting forms the main frame part of the machine which includes the most of an expanded base 1, the major por-

tion of a hollow substantially rectangular standard 2 which rises from the hollow base 1, and also comprises a top wall 3 for the upper end of the standard 2, which forms the bottom of a container for the liquid. The lower portion of the front of the standard 2 and the upper front portion of the base 1 are formed by a die-cast removable front door 4, which has an interlocking engagement at its upper end as shown in Figs. 3, 8 and 10, and which is secured in place at its base end by means of an ordinary lock 5 which has locking detachable engagement with the upper end of a lock stud 6, secured to the bottom of a money pan 7 which telescopes into the bottom of the base 1 and is also removably held in place by means of the lock 5. Internal frame parts for carrying various parts of the operating mechanism comprise a lower bracket member 8 which is secured to the rear wall of the standard 2 by means of a pair of screws 9, a mechanism frame 10 similarly secured to the rear wall of the standard 2 by means of a pair of screws 11, and a dial-forming indicator frame 12 in the upper and forward part of the standard 2 which is secured to the front and upper part of the mechanism frame 10 by means of a pair of screws 13 which are screwed in from the back of the mechanism frame 10, these frame parts 10 and 12 being provided with abutting spacing bosses to receive these screws 13. These frame parts 8, 10 and 12 may all conveniently be zinc die-castings.

An upright cylindrical glass container body 14 rests upon a shoulder formed within a peripheral upstanding flange 15 on the projecting dish-shaped standard top 3 which thus forms the bottom of the container, this joint being provided with a gasket 16. The upper end of the glass container body 14 is provided with a die-cast cover cap 17 which is flanged downwardly around its periphery and is there provided with a sealing gasket 18. The central portion of this cover cap 17 projects upwardly in the form of a housing 19 for accommodating internal parts which project upwardly above the top of the container body 14. The front of this housing 19 is of circular shape and carries a name plate 20 which indicates the use of the machine, that is, the nature of the liquid vended. The container body 14 and its cover cap 17 are firmly clamped and rigidly secured in place by means of three screw bolts or rods 21 which pass through the cover cap 17 and screw into lugs 22 formed on the container bottom 3. Near its rear edge the cover cap 17 is provided with a screw plug 23 for filling the container.

An upright pump cylinder 24 has its lower end securely sealed against the upper surface of the container bottom 3 by means of an interposed gasket 25 and is firmly secured to the container bottom by means of a pair of screws 26 which pass through lugs as shown

provided on the lower end of the cylinder. The lower end of this pump cylinder 24 is provided with a sealed outlet or delivery passage 27 which extends laterally into a lug 28 provided on the cylinder. A small delivery tube 29, which may suitably be of copper, is sealed into the lug 28 in communication with the cylinder passage 27 and together therewith forms a continuously freely open outlet or discharge conduit from the bottom of the cylinder 24. This outlet tube 29 extends upwardly above the liquid level and above the top of the container body 14 into the housing portion 19 of the cover cap 17 and its upper end has a freely open outlet turned downwardly. The down-turned upper end of the small outlet tube 29 loosely enters and freely opens into the upper end of a considerably larger vertical overflow pipe 30, which may be of brass, having its lower end screwed into the container bottom 3. A delivery spout 31 communicates with the lower end of the overflow pipe 30 and extends to the outside of the machine where it projects at the left side of the upper portion of the standard 2 below the container bottom 3. This spout 31 may be a piece of bent copper tubing cast into the main frame part of the machine as an insert.

The pump cylinder 24 is provided with a pair of oppositely arranged spaced upward extensions 32 which form a piston guide without adding anything to the effective length of the cylinder 24. A piston 33 of inverted cup shape is adapted to reciprocate into and out of the open upper end of the cylinder 24, being guided by the guide extensions 32 when it rises above the top edge of the cylinder 24 between these rather widely spaced piston guides. Since the piston 33 when it is reciprocated rises at its lower edge above the open top of the cylinder 24, it is obvious that this cylinder can then freely fill with the liquid without need of providing any inlet valve for this purpose. However, in such a construction, when the piston rises in the cylinder, it would have a tendency to draw air into the cylinder through the small outlet tube 29, after of course first drawing out the small quantity of the liquid contained in this tube. Therefore, the top web of the piston 33 is provided with a suitable number of relief openings as shown in Fig. 5 which are controlled by an inwardly opening valve 34 of substantially a usual form. The cylinder part may be a zinc die-casting, while the piston and its valve may suitably be of brass.

The piston 33 is further guided between the cylinder extensions 32 by means of a pair of top extensions 35 on the piston which have inner plane opposed faces spaced apart to the same extent as the spacing between the piston guides 32 at their opposed edges so that thereby a large slot is provided which comprises the space between the two piston guides 32 and the space between the two piston exten-

sions 35. A piston pin 36 extends between and is fixed at its ends in the respective piston extensions 35.

An operating link 37, which may be a brass stamping, is provided at its lower end with an eye by which it is pivoted on the piston pin 36. This link extends upwardly at a slight outward inclination and at its upper end is turned outward horizontally. This turned over upper end of the link 37 has rigidly connected thereto the upper end of a vertical slideable operating rod 38 which extends downward through and projects for some distance below the container bottom 3. This connection between the piston link 37 and the operating rod 38 is made by means of a rather extended threaded portion on the upper end of the rod which passes through the end of the link, which is firmly held and clamped in place between a pair of nuts 39, thereby providing an adjustable connection between the piston link 37 and its operating rod 38 by reason of which, as will presently more clearly appear, the piston 33 may be adjustably raised or lowered in the cylinder 34 for thereby varying the effective length of the stroke of the piston without any change in the actual length of the path of its reciprocating movement. Such adjustment obviously will correspondingly vary the measured quantity of the liquid delivered from the cylinder, by reason of the fact that the length of the path of travel of the piston within the cylinder below the upper end of the latter may thus be made longer or shorter.

The upper end of the operating rod 38 as well as the piston link 37 extends above the top of the container body 14 into the lower part of the housing 19. The slideable operating rod 38 is provided with a guide tube 40 forming a liquid tight sleeve which at its upper end is somewhat above the upper end of the container body 14 and which at its lower end screws with a sealing fit into the container bottom 3, which it is shown as passing through and forming a rod guide therein (Fig. 5). It may be noted that the side of the hollow standard 2 adjacent to its base 1 and in line below the spout 31 is provided with a drip trough 41 from which any drippings may drain into the casing and be caught by the money pan 7 from which they will quickly and harmlessly evaporate.

In the embodiment of the invention shown the piston 33 is normally at its lowermost position in the cylinder 24 and at each operation of the machine is lifted out of the cylinder and is again returned in its delivery stroke to its lowermost normal position, thus performing a single complete reciprocation for each time the machine is operated. Thus the sliding operating rod 38 may be termed a lift rod since it first raises the piston 33 before it imparts to this piston its downward

delivery stroke. The portion of the lift rod 38 which extends below the container bottom 3 and the lower end of the guide sleeve 40 passes through and is slidably guided in a bearing provided by the inner frame part or mechanism frame 10 and this rod normally projects freely downward below this bearing to an extent substantially equal to or a little greater than the extent of its sliding movement and terminates in a rounded lower end. This lift rod 38 is provided with a stop pin 42 which limits its downward movement by abutting against the top of the bearing formed by the frame part 10. Other stop means for this lift rod will hereinafter appear. Above this stop pin there is a washer 43 and on the lift rod 38 interposed between this washer and the lower end of the guide sleeve 40 there is a rather strong coiled thrust spring 44. It will now be clear that if the operating rod 38 is lifted and then released the spring 44 will return this rod to its lowermost position and thereby impart a delivery stroke to the piston 33. The lift rod 38 and its guide sleeve 40 may be of brass.

A rocking operating lever 45 has a cam toe which engages the rounded lower end of the lift rod 38. Forwardly from the lower end portion of the lift rod 38, this operating lever 45 is pivoted on a pin 46 which is carried by a pair of spaced forwardly projecting ribs formed on the inner frame piece 10, the lever 45 being guided between these ribs as is clearly shown in the drawings. Above and forwardly from its pivot pin 46 the operating lever 45 is provided with a relatively short tail arm by which this lever is stopped against the lower side of the indicator frame 12, as shown in Figs. 3, 8 and 10, which thereby also forms a further stop for the lift rod 38 against the downward thrust of its spring 44. The operating lever 45, which desirably is a hardened steel stamping, is of a flat substantially triangular shape so that virtually or in effect it forms a bell-crank lever. One arm of this triangular bell-crank lever engages with the lower end of the lift rod 38 while its other arm, which is about the same length or a trifle longer, extends downwardly from the pivot pin 46 and terminates at its lower end in a downwardly projecting rounded lug by means of which the operating lever 45 may be actuated or rocked in its operation, by imparting rearward movement to this downwardly projecting lug or lever end.

So far as the dispensing mechanism of the invention is concerned, any suitable manually operable device may be provided for thus actuating or rocking the operating lever 45, such for example as a usual simple form of plunger projecting from the front of the machine, or by means of a simple rocking actuating lever provided with a suitable handle at the outside of the machine. However, in the more desirable embodiment of

the invention shown, the manually operable device for actuating the rocking operating lever 45 is coin controlled. These coin controlled parts of the operating mechanism 5 will be described somewhat farther along, since at this point it is thought desirable to describe the mechanism of the hereinbefore noted indicating device which is employed in carrying out the invention for giving at any 10 time a visual indication of the number of delivery operations to which the machine has been subjected. Such indicator may be considered as constituting a simplified form of cash register which will indicate the number of 15 sales which have been made, and correspondingly of course the amount of cash which has been, or which should have been, taken in, regardless of whether or not the delivery operations of the machine are controlled by 20 the deposit or insertion of a coin therein.

The indicator mechanism will now be described. A circular window opening is provided in the front and near the top of the hollow standard 2 and is closed by a glass plate 47, held in place by means of a bezel ring 48, which is flanged inwardly over the front of the glass and flanged outwardly at the inner side of the wall of the standard. At 25 its front the indicator frame 12 has a rather deep flange which fits up against the edge of the glass 47 and its bezel ring 48. The exposed front surface of the front plate of this 30 indicator frame 12 forms a dial, which in the particular construction shown in the drawings is graduated or calibrated in units running from one to one hundred, every tenth unit being indicated by a longer calibration mark and by a single numeral, running from 35 one to nine, excepting at the combined starting and ending point at the top, which is left blank.

A large or long indicating hand 49 moves 40 step by step over the dial for giving unit indications, thus moving one step or unit indication at each operation of the machine, so that thereby obviously this long outer or forward hand 49 will directly indicate or count the operations of the machine unit by unit from one to one hundred. At the rear 45 of the long hand 49 is a short or medium length intermediate hand 50. At each actuation of the machine, this medium hand 50 moves angularly over only one-tenth of the distance covered by the units hand 49. Thus 50 when the units hand 49 has made one rotation, to give an indication of one hundred, then the medium hand 50 will have covered ten unit spaces and will stand at the numeral 55 1 on the dial, thereby also indicating one hundred, according to this hand 50. After this, for succeeding operations of the machine, these two hands 49 and 50 are to be read together. For example, when the unit hand 49 has moved again over the first 60 ten units indication and reached the numeral 65

1, the reading will then be 110, the hundred being indicated by the fact that the medium hand 50 has reached and passed this numeral 1, while the units to be added are indicated by the unit hand 49 having now 70 reached this numeral 1. Accordingly it will be clear that one complete rotation of this intermediate medium length hand 50 will give an indication on the dial of one thousand, since each of the numerals on the dial represents an indication of one hundred for this hand, so that, for example, when this medium hand 50 reaches the numeral 9, it will indicate 900. This medium length hand 50 is therefore a hundreds hand. Inward from 75 the intermediate medium length hundreds hand 50, there is a small or short hand 51, which is a thousands hand, by reason of the fact that in its movement it covers one-tenth of the angular distance of the medium length 80 or hundreds hand 50, and correspondingly covers one one-thousandth of the angular distance covered by the units hand 49. Thus when this thousands hand 51 stands at the numeral 1 on the dial, it will indicate one 85 thousand. It will thus be readily understood that by reading the dial indications of the three hands together, unit indications up to 9,999 may be determined, which will then be the indication of the number of operations of 90 the machine. One more operation of the machine will bring all of the hands together at the blank indication at the top, thereby indicating that the machine has been operated ten thousand times, after which the counting operation of the indicator starts all over again.

The mechanism shown in the drawings for thus operating these three hands 49, 50 and 51 will now be described. All of these hands are in axial alignment with their common axis at the center of the dial. The units hand 49 is carried upon the forward end of a shaft 52 which extends to the rear through the dial plate of the indicator frame 12 and at its rear end is journaled in a bearing provided on the mechanism frame 10. This shaft 52 rotatably passes through and projects at both of its ends beyond an intermediate sleeve 53 which passes through the dial plate and at its forward end carries the medium length intermediate hundreds hand 50. This intermediate sleeve 53 rotatably passes through and projects at both of its ends beyond a shorter outer sleeve 54 which is journaled directly in the dial plate of the indicator frame 12 and at its forward end carries the short or thousands hand 51.

A large spur gear 55 is fixed on the units hand shaft 52 adjacent to the front side of its bearing in the mechanism frame 10. This gear 55 forms a part of the operating mechanism for driving the entire indicator mechanism, which will be presently described. It may be noted, however, that this driving de-

vice for the indicator moves the gear 55 forward step by step to the extent of one units indication of the units hand 49, each time that the hereinbefore described delivery mechanism is operated.

Transfer mechanism is provided between the units hand shaft 52 and the hundreds hand sleeve 53, and also similarly between the latter sleeve and the thousands hand sleeve 54, this transfer mechanism being in the form of continuously intermeshing gears. The large drive gear 55 carries a spur pinion 56 on its forward side formed in the same piece therewith as a hub thereon. This pinion 56 engages with a spur gear 57 which has, formed in the same piece therewith as a hub on its forward side, a spur pinion 58 which engages with a spur gear 59 fixed upon the rear end of the intermediate sleeve 53 which carries the hundreds indicating hand 50. The pinion 56, gear 57, pinion 58 and gear 59 constitute continuously engaged transfer means from the units indicating shaft 52 to the hundreds indicating sleeve 53, the ratio of which is as ten to one, that is to say, it will require ten rotations of the shaft 52 in order to impart one complete rotation to the sleeve 53.

Similar transfer means are provided from the hundreds indicating sleeve 53 to the thousands sleeve 54, comprising a spur pinion 60 in the same piece with and forming a hub on the forward side of the gear 59, engaging with a spur gear 61 carrying on its forward side a spur pinion 62 forming a hub thereon in the same piece therewith and which is in engagement with a spur gear 63 which is fixed upon the rear end of the short outer sleeve 54 which carries the thousands indicating hand 51. The ratio of this continuously engaged transfer gearing from the intermediate sleeve 53 to the outer sleeve 54 is also ten to one.

Thus it will be seen that the comparative extent of angular movement between the units indicating hand 49 and the hundreds indicating hand 50 is as ten to one, and similarly between the hundreds indicating hand 50 and the thousands indicating hand 51 the comparative extent of angular movement is also as ten to one, and that accordingly the comparative extent of the angular movement between the units indicating hand 49 and the thousands indicating hand 51 is as one hundred to one. The two transfer gears 57 and 61 are independently loosely journaled upon a stud shaft 64 which at its forward end is rigidly fixed in the dial plate of the indicator frame 12, the rearmost transfer gear 57 being positioned on the shaft by the front face of the contiguous drive gear 55.

The large drive gear 55 is continuously engaged with and is driven by a pinion 65 which is formed in the same piece and as a hub on the forward side of a ratchet wheel 66. This

ratchet wheel 66 with its pinion 65 is journaled on the middle portion of a shaft 67, the rear end of which enters the mechanism frame 10 and the forward end of which enters the rear end of a boss formed on the indicator frame 12, so that this ratchet wheel with its pinion is rotatively confined between these two frames, with the upper portion of the ratchet wheel just at the rear of the lower portion of the drive gear 55. When viewed from the front, as seen in Figs. 2, 7 and 11, it will be noted that this ratchet wheel shaft 67 is located below and considerably to the left side of the gear shaft or units hand shaft 52 so that the toothed periphery of the ratchet 66 is just at the left of a vertical plane passing through the axis of the shaft 52.

The ratio of drive for each tooth, or from tooth to tooth, of the ratchet wheel 66 to the units indicating shaft 52 is as one hundred to one. That is to say, each time the ratchet wheel 66 moves over the angular distance between two of its teeth, the units indicating hand 49 will move over a single units indication on the dial. For example, the ratchet wheel 66 may have twenty-five ratchet teeth, its pinion 65 may have twelve teeth and the drive gear 55 may have forty-eight teeth. It might be noted that this ratchet wheel together with all of the above described gear wheels in the indicator mechanism may conveniently be zinc die-castings.

The device by which the ratchet wheel 66 is driven or actuated step by step one tooth at a time for each operation of the above described delivery mechanism will now be described. This ratchet wheel 66 is provided with a holding pawl 68, shown as in the form of a bent leaf spring the remote end of which is provided with an eye which fits over an anchor pin 69, which may be cast upon the wall of the mechanism frame 10 which extends just at the rear of the ratchet wheel 66. This spring holding pawl 68 is prevented from rotating on its anchor pin 69 by means of a holding pin 70 which at its rear end is fixed in the mechanism frame 10 and the forwardly projecting end portion of which is split to form a slot which receives the spring pawl 68 at an intermediate point thereon suitably spaced from the anchor pin 69, as is most clearly shown in Fig. 11. The free end of this spring pawl 68 engages between two of the teeth of the ratchet wheel 66 for normally holding this wheel stationary while at the same time providing for its rotative movement in one direction only when actuating force is applied thereto. In the construction shown, the direction of rotation of this ratchet wheel 66 is counter-clockwise as viewed from the front, so that thereby its toothed periphery at the right side of its shaft 67 will move upwardly.

A spring-pressed pawl-carrying operating lever 71 for the ratchet wheel 66 is pivoted

on the front and near the lower right hand corner of the mechanism frame 10 on a pivot stud 72 which may be cast upon this frame piece. This indicator operating lever 71, which may be a flat steel stamping, is straight along its lower edge and extends to the left in the form of an arm, the free end portion of which overlies the slot formed between the guide ribs on the frame piece 10 for the operating lever 45, which is a part of the delivery mechanism of the machine. It will be noted that flanges or webs are formed on the frame piece 10 at opposite sides of the upper edges of the guide ribs and that the slot for accommodating the operating lever 45 extends upwardly above these flanged ribs into the upright portion of the frame piece 10 at the back of the ratchet-operating lever 71.

This ratchet lever 71 is in general of substantially triangular shape, thereby to provide thereon an upper arm which extends angularly inward. This ratchet lever 71 is provided with a fairly strong return spring 73, which is a coiled compression spring engaging over a small lug formed on the upper arm of this lever 71 and at its other end this spring 73 is seated in a socket-forming projection 74 on the front face of the frame piece 10. The ratchet-operating lever 71, which is a pawl lever, carries a spring driving pawl 75, the construction of which per se may be the same as that of the holding pawl 68. The right or shank end portion of this spring pawl, which carries an eye at its end, is anchored in a slot cut into the pawl lever 71 from its left hand end, and from the point where this flat spring pawl 75 emerges from this slot the spring pawl, by reason of a bend therein, projects inwardly and upwardly with its free end normally in engagement between two of the teeth of the ratchet wheel 66 at the right of the periphery of the latter.

When the pawl-carrying lever 71 is rocked upwardly its spring pawl 75 will impart rotative movement to the ratchet wheel 66 and when this pawl-operating lever 71 is released it will be returned to its normal position shown in the drawings by its spring 73, which is stronger than the spring pawl 75, which accordingly will be moved over the teeth of the ratchet wheel 66, the latter being held against reverse rotation by the holding pawl 68. In the operation of the indicator device, this operating lever 71 will thus be lifted the correct distance for rotating the ratchet wheel to the extent of a single tooth movement or step, the return spring 73 then acting to reset the indicator-operating lever 71 and its spring drive pawl 75 to normal position, for a subsequent operation. In the embodiment of the invention shown in the drawings, this indicator-operating lever 71 will be thus lifted by the upper edge portion of the underlying operating lever 45 each time

this latter lever is operated for effecting a delivery of a predetermined measured quantity of the liquid, as hereinbefore described.

The manually operable device for actuating the operating lever 45 remains to be described, and in the embodiment of the invention shown in the drawings this is a coin controlled device, by reason of which the hereinbefore described delivery mechanism or dispensing mechanism is normally inoperable, the manually operable operating device or driving device being made effective for this purpose by the insertion of a proper coin. These coin controlled parts of the complete operating mechanism of the illustrated coin controlled vending machine will now be described.

Near its upper end the front door piece or plate 4 is provided with an outer recess 76 which forms the entrance way for a coin. This entrance way 76 is vertically of a flaring triangular shape, as shown in Figs. 3 and 8, and has its upwardly and inwardly inclined bottom wall convexly curved to fit the lower edge of a proper coin while it is open freely outwardly with a flat downwardly and inwardly inclined upper wall for guiding the flat side of the coin. The coin is thence guided downwardly at its edges in a coin slot 77 which at the front and in the lower parts thereof is in part formed by the inner inwardly and downwardly inclined flat end surface of a lug 78 formed on the inner side of the door plate 4 below the coin entrance 76. This coin slot 77 at its upper and inner part is also in part formed by means of an inner coin guide 79 which is in the form of a short flat bar notched at the middle on its lower edge and at its opposite ends rigidly secured in place on the inner side of the door plate 4 by means of a pair of screws 80, one of which appears in Fig. 10.

An operating handle 81, which may be a zinc die-casting, is shown at the right side of the machine just above the base 1 as an upstanding lever arm to be pushed rearwardly and downwardly. This handle lever 81 has a hub portion 82 which is journaled in a bearing provided in the wall of the standard 2. The notched and squared end portion of a handle shaft 83 is cast as an insert into the hub 82 and adjacent end of the handle lever 81, whereby the handle 81 and its shaft 83, which may be of steel, are rigidly and firmly secured together. The other end of this handle shaft 83 is journaled in a bearing formed on the opposite wall of the standard 2. Within the hollow standard 2 the handle shaft 83 carries a coin carrier 84 through the lower end of which it passes and in which this shaft is removably fixed. This coin carrier 84 is in general of substantially an inverted U shape as probably appears most clearly in Fig. 7, with the handle shaft 83 passing through the lower ends of its arms, so that this coin car-

rier 84 in general forms an upstanding lever which in its normal position projects upwardly at a forward inclination as shown in Figs. 3 and 8.

The coin carrier 84 at the lower ends of its spaced arms is shown as provided with hub portions the ends of which fit up against the inner sides of the opposite walls of the standard 2 surrounding the handle shaft 83. The 10 coin carrier 84 is firmly and rigidly secured to this handle shaft 83 by reason of the squared end portion of the shaft adjacent to the handle hub 82 fitting snugly in a square hole through the adjacent coin carrier hub 15 end, the handle shaft 83 being anchored to this hub end of the coin carrier by means of a screw 85 the inner end of which engages in a recess in the squared portion of the handle shaft 83, as shown in Figs. 2 and 7, so that 20 thereby the coin carrier 84 and the handle shaft 83 are held in place and the latter cannot be withdrawn.

The coin carrier 84 will be stopped in its 25 rearward rocking movement by reason of its upper end at the sides thereof at the back abutting against the front face of an upper forwardly offset portion on the bracket member 8, and in its return movement to its normal position the coin carrier 84 will be 30 stopped by a pair of rear oppositely opposed stop lugs 86 thereon abutting against the lower sides of lateral forwardly projecting shoulders formed on the lower part of the bracket member 8, as shown in Figs. 3, 8, 9 35 and 10. The coin carrier 84 at the left side thereof is provided with a downwardly projecting tail arm 87 to the end of which there is connected the forward end of a coiled retractile return spring 88 for the coin carrier 84, the other end of this spring being anchored to the adjacent wall of the standard 2 by means of a screw 89, as shown more particularly in Figs. 3 and 8.

The transverse bar of the coin carrier 84 at 45 the top thereof is provided on its rear side with a deep and wide transverse notch, forming opposed lateral shoulders, as shown in the drawings, more clearly in Fig. 9. These shoulders, adjacent to but slightly spaced 50 rearwardly from the bottom of the large slot formed between them, are provided with a pair of opposed rather deep substantially radial grooves 90 which extend entirely through from the top to the lower side of the 55 coin carrier bar, for receiving therein the lateral edge portions of a coin 91, as is shown most clearly in Fig. 2. These coin carrier slots or grooves 90 are normally in alignment with the coin slot 77, so as to receive the 60 inserted coin 91 therefrom.

The top bar of the coin carrier 84 has a 65 forwardly extending ledge 92 which is arcuate on its upper surface and which along its upper side margins is provided with a pair of arcuate ribs 93, the rear ends of which are in

line with the adjacent faces of the coin-receiving slots 90, and the upper arcuate surfaces of which extend forwardly and downwardly from the coin slot 77 along the lower correspondingly curved surface of the casing lug 78. The purpose of these ribs 93 is to provide a rest for the lower edge of a coin should such coin be inserted through the coin slot 77 while the coin carrier 84 is out of its normal position, that is, when the coin carrier has been rocked rearwardly. This prevents the loss of coins in the machine, and when the coin carrier has returned to its normal position such a coin would then drop from the coin slot 77 into the coin carrier slots 90.

The lower part of the bracket member 8, which is secured by the screws 9 to the adjacent wall of the standard 2, is provided at its respective sides with a pair of forwardly extending lugs or arms 94, the lower edges of which towards the rear form the hereinbefore mentioned stop shoulders for the coin carrier lugs 86. The forward ends of these lug arms 94 are connected together by a cross piece or bar 95 the upper side of which is provided with a coin-guiding surface 96, this surface from front to rear forming an arcuate convex curve which is the same as the arcuate curve of the path of travel of the coin carrier, this surface 96 also being concavely curved from side to side or laterally to the arcuate contour of the edge of the coin. This coin-guiding and supporting surface 96 extends across from the front to the rear of the top of the cross bar 95.

The rear side of this cross bar 95 forms a substantially vertical surface which is substantially in line with the axis of the handle shaft or coin carrier shaft 83, while the forward side of this cross bar together with its coin-guiding surface 96 is somewhat forward of the radially aligned coin-insertion slot 77 and the coin-receiving slots 90 in the coin carrier 84 when the latter is in its normal position shown in the drawings. Thus an inserted coin such as the coin 91 in the coin carrier slots 90 will rest at its lower edge upon and be supported by the curved surface 96 on the cross bar 95, which is cast in the same piece with the bracket member 8. When the coin carrier 84 has been rocked to its rearward position, the coin 91 will pass beyond the end of the coin-supporting surface 96 and beyond the rear flat face of the bar 95, and will accordingly be free to drop into the bottom of the casing where it will be received in the money pan 7.

It will be noted from the drawings, particularly Figs. 8 and 10, that the hereinbefore described operating lever 45 has thereon a rounded downward projection or lug 97 which is just at the front of and in the path of rearward movement of the upper edge portion of the coin 91. Therefore, if the coin carrier 84 is rocked while it carries a coin,

130

the coin carried thereby will rock the operating lever 45 in the manner hereinbefore described, for effecting the delivery of a predetermined measured quantity of the liquid.

5 When the coin carrier carries no coin, it is obvious that it may rock freely back and forth without effecting any result. The coin 91 merely forms a temporary extension of the length of the lever arm formed by the coin carrier 84 and is then released from the coin carrier in the manner above noted. When the operating lever 45 has been thus rocked to its operated position, the resulting angularly inclined position of its lug 97 together with the rounded contour of this lug will cause this lug to have a cam action upon the upper edge of the coin in the coin carrier by reason of which the coin is pushed downwardly, which facilitates the quick release and downward dropping of the coin 91, as will be readily understood.

It is important that the coin carrier 84 when it carries a coin should be compelled to move completely to its rearward position 25 for discharging the coin without permitting it to return from any intermediate position to or towards its normal position in which it is shown in the drawings. Otherwise it is obvious that the coin carrier could be 30 rocked back and forth to and from an intermediate position and unlimited quantities of the liquid thereby obtained by the use of only a single coin. Accordingly, in order to prevent this, a pair of forwardly extending coin 35 ratchet pawls 98 and 99 are located one at each side of the lower portion of the operating lever 45, and at the rear are pivoted on a pin 100 which extends between a pair of upstanding lugs 101 on the top of the bracket member 8, a spacing collar 102 (Fig. 9) being 40 provided on the pivot pin 100 between these ratchet pawls.

Each of these coin ratchet pawls 98 and 99 is provided at its rear or pivoted end with 45 a tail arm which projects downwardly between the casing wall of the standard 2 and the rear face of the forwardly offset upper portion of the bracket member 8, each of these tail arms being urged rearwardly 50 by a coiled thrust spring 103 which is seated in a socket provided in the back of the bracket 8. This bracket below and forwardly from the pawl pivot pin 100 forms a stop shoulder for both of these coin ratchet pawls against 55 which they are normally pressed by their springs 103, each of these pawls 98 and 99, however, acting independently of the other.

These two ratchet pawls 98 and 99, which 60 may be steel stampings, are both alike with the exception that the pivot hole for the pivot pin 100 in the left hand ratchet pawl 99 is located farther forwardly in the pawl arm than is the pivot hole in the right hand ratchet pawl 98 (Figs. 8, 9 and 10). The 65 right hand ratchet pawl 98 projects for-

wardly and terminates in a rounded end closely adjacent to the rear face of and near the upper edge of the coin 91 in the coin carrier (Fig. 8), while the forward end of the similarly shaped left hand ratchet pawl 99 is a little farther to the rear (Fig. 10).

These pawls 98 and 99 each has a smooth shank portion adjacent to its pivot pin 100 after which for the rest of its length out to its forward end it is provided on its lower edge with a series of ratchet teeth the front faces of which incline rearwardly while the rear faces of these teeth are abrupt, the notches provided between these teeth being adapted to receive into them the upper edge of the coin 91 as it is moved forward by the coin carrier. It is to be noted that the ratchet teeth of these respective pawls alternate with each other, that is to say, the pawl teeth in one of the ratchet pawls come even with or opposite to the notches between the pawl teeth in the other ratchet pawl. Thus when the coin carrier 84 carrying a coin 91 is rocked rearwardly, the upper edge of this coin will engage alternately with the teeth of the respective coin ratchet pawls 98 and 99, thereby cutting in half the amount of lost motion in the return movement of the coin carrier with the coin, before such return movement is stopped by a tooth of one of the ratchet pawls. This arrangement renders it impossible to obtain more of the liquid than has been paid for. It also assures the delivery of a uniform measured quantity of the liquid at each successive operation of the machine. In this connection, it will be noted as obvious that the homologue of this feature could also as well be embodied in a substantially similar dispensing device without coin control, for similarly assuring successive uniform deliveries.

The hereinbefore mentioned notch in the lower edge of the coin guide 79 is to provide clearance for the lug end 97 of the operating lever 45 and similarly for the forward ends of the coin ratchet pawls 98 and 99, as will be clear from Figs. 3, 8 and 10, so that these parts may come close up to the coin 91. It will be noted that the forward edge of the operating lever 45 near its lower end lug 97 is provided with a rounded projection by which in its return movement this operating lever will be stopped against the upper portion of the coin guide 79, additionally to the above noted stop provided by its top projection against the lower side of the indicator frame 12. When the coin drops from the coin carrier it will strike a bell 104 for announcing to the customer that the machine has been fully operated.

It is thought that the operation of all of the parts and features of the vending machine have been fully described in connection with the description of the construction and that therefore there is nothing which need

be added in this respect. Vending machines constructed substantially as shown in the drawings and above described have been found to operate successfully, substantially in the manner hereinbefore described.

5 It is obvious that various modifications may be made in the construction shown in the drawings and above particularly described, within the principle and scope of the invention as defined in the appended claims.

10 I claim:

1. In a machine for vending liquid, a container for the liquid, an open top upright cylinder fixed to the bottom of the container and provided at its open upper end with side extensions forming piston guides, a piston to reciprocate into and out of the open upper end of the cylinder, a freely open delivery tube communicating with the lower end of 20 the cylinder below the piston and having an open upper discharge end above the top of the container, an operating link connected to the piston and extending at its upper end above the top of the container, an operating 25 rod connected at its upper end to the upper end of the said link and extending downwardly through and beyond the bottom of the container, a liquid tight guide sleeve for the said operating rod rigidly carried by and 30 projecting upwardly from the bottom of the container and terminating at its upper end above the top of the container, and manually operable means engaging with the lower end of the said operating rod to reciprocate the 35 latter in a similar manner at each operation of the machine for thereby delivering a measured quantity of the liquid.

2. The invention defined in claim 1, in combination with an adjustable connection of 40 the said sliding operating rod at its upper end with the upper end of the piston link comprising a pair of nuts screwed on the upper end of the rod and clamping between them the upper end of the link through 45 which the rod passes for thereby adjustably varying the extent to which the piston in its delivery stroke will enter the open upper end of the cylinder for correspondingly varying in a predetermined manner the measured 50 quantity of the liquid to be delivered at each operation of the machine.

3. The invention defined in claim 1, in combination with an overflow pipe rigidly carried by and extending from the bottom of 55 the container upward above the top thereof and into the upper end of which the said delivery tube discharges while leaving the upper end of the overflow pipe open to the air, and a delivery spout communicating with 60 the lower end of the overflow pipe and having a delivery end at the outside of the machine.

4. The invention defined in claim 1, in combination with a spring acting upon the 65 said sliding operating rod to move the latter

downward for thereby imparting a downward delivery stroke to the piston, a rocking operating lever engaging with the lower end of the operating rod to lift the latter against the force exerted by the spring, and a manually operable device including a handle for 70 rocking the said lever to lift the operating rod.

5. The invention defined in claim 1, in combination with an adjustable connection 75 of the said sliding operating rod at its upper end with the upper end of the piston link comprising a pair of nuts screwed on the upper end of the rod and clamping between them the upper end of the link through which the rod passes for thereby adjustably varying the extent to which the piston in its delivery stroke will enter the open upper end of the cylinder for correspondingly varying in a predetermined manner the measured 80 quantity of the liquid to be delivered at each operation of the machine, an overflow pipe rigidly carried by and extending from the bottom of the container upward above the top thereof and into the upper end of which the said delivery tube discharges while leaving the upper end of the overflow pipe open to the air, a delivery spout communicating with the lower end of the overflow pipe and having a delivery end at the outside of the 85 machine, a spring acting upon the said sliding operating rod to move the latter downward for thereby imparting a downward delivery stroke to the piston, a rocking operating lever engaging with the lower end of the operating rod to lift the latter against the force exerted by the spring, a manually operable device including a handle for rocking the said lever to lift the operating rod, and a cover cap for the top of the container 90 providing a housing for the said parts which project from within above the top of the container and including the upper end of the piston link, the upper end of the said operating rod, the upper end of the guide sleeve for 95 the latter, the upper end of the overflow pipe and the upper end of the discharge tube which opens into the latter.

6. In a machine for vending liquid, a container for the liquid, a cylinder to be submerged in the liquid in the container and fully open at one end into the liquid, a freely open discharge conduit communicating with the other end of the cylinder and rising above the level of the liquid in the container, a reciprocating piston which when retracted moves entirely out of the open end of the cylinder and which in its delivery stroke moves back into the cylinder, manually operable means for uniformly reciprocating the piston at each operation of the machine thereby to deliver a uniform measured quantity of the liquid at each of such operations, and means for effecting a relative adjustment in position between the cylinder and the piston 115 120 125 130

by which the extent to which the piston moves into the cylinder in making a complete to and fro reciprocation may be varied thereby to vary the effective length of the stroke of the piston while still maintaining the actual length of this stroke thus to vary in a predetermined manner the uniform measured quantity of the liquid which will be delivered at each operation of the machine.

7. In a machine for vending liquid, a container for the liquid, a pump cylinder in communication with the liquid in the container, a piston to reciprocate in the cylinder, means dependent upon the retraction of the piston to admit liquid from the container into the cylinder at the front of the piston, a discharge conduit communicating with the cylinder at the front of the piston, manually operable operating mechanism for the piston which compels uniform reciprocating movement of the piston at each successive operation of the machine thereby successively to deliver uniform measured quantities of the liquid, the said operating mechanism including a uniformly movable operating handle and operating connections interposed between the handle and the piston, and means for effecting adjustment to vary in a predetermined manner the measured quantity of the liquid to be delivered at each operation of the machine while still maintaining the uniform operating movement of the handle.

8. In a machine for vending liquid, a container for the liquid, an upright cylinder in the bottom of the container, a discharge conduit leading from one end of the cylinder, a piston to reciprocate in the cylinder, means effective upon reciprocation of the piston to withdraw liquid from the container and discharge it through the said conduit, an operating link connected to the piston and extending at its upper end above the level of the liquid in the container, a sliding operating rod connected at its upper end to the upper end of the said link and extending downwardly through and beyond the bottom of the container, a liquid tight guide sleeve for the said operating rod rigidly carried by and projecting upwardly from the bottom of the container and terminating at its upper end above the level of the liquid in the container, and manually operable means engaging with the lower end of the said operating rod to reciprocate the latter in a similar manner at each operation of the machine for thereby delivering a measured quantity of the liquid.

9. The invention defined in claim 8, in which the cylinder is open at its upper end and the piston reciprocates into and out of this open upper end of the cylinder, in combination with a vertically adjustable connection of the said sliding operating rod at its upper end with the upper end of the piston link for thereby adjustably varying the extent to which the piston in its delivery stroke

will enter the open upper end of the cylinder for correspondingly varying in a predetermined manner the measured quantity of the liquid to be delivered at each operation of the machine.

10. The invention defined in claim 8, in which the said discharge conduit is a freely open delivery tube having an upper discharge end above the level of the liquid in the container, in combination with an overflow pipe rigidly carried by and extending from the bottom of the container upward above the level of the liquid therein and into the upper end of which the said delivery tube discharges while leaving the upper end of the overflow pipe open to the air, and a delivery spout communicating with the lower end of the overflow pipe and having a delivery end at the outside of the machine.

11. The invention defined in claim 8, in which the said discharge conduit leads from the lower end of the cylinder, in combination with a spring acting upon the said sliding operating rod to move the latter downward for thereby imparting a downward delivery stroke to the piston, a rocking operating lever engaging with the lower end of the operating rod to lift the latter against the force exerted by the spring, and a manually operable device including a handle for rocking the said lever to lift the operating rod.

In witness whereof, I hereunto subscribe my signature.

LOUIS H. MORIN.
